BALANCED MODULATOR SYSTEM

Hershel Toomim, Great Neck, N. Y., assignor to
Press Wireless, Inc., Chicago, Ill., a corporation
of Delaware

Application September 11, 1943, Serial No. 501,928

6 Claims. (Cl. 179—171.5)

This invention relates to modulating systems and more especially to electron tube modulators of the balanced type.

A principal object of the invention is to provide an improved double-balanced modulator.

Another object is to provide an improved double-balanced modulator of the type wherein two input frequencies are intermodulated to produce in the output their sum and difference frequencies without any appreciable presence of either of the input frequencies.

Another object is to provide an improved double-balanced modulator wherein two input frequencies are intermodulated to produce in the output their sum and difference frequencies without any appreciable presence of the harmonics of the signal input frequencies.

Another object is to provide an improved inverting network especially useful in secrecy transmission and the like, whereby a normal intelligence frequency e. g., 200 C. P. S. can be converted into a higher frequency signal e. g., 2000 C. P. S.

A feature of the invention relates to a stable and relatively cheap double-balanced electron tube modulator.

Another feature relates to a double-balanced electron tube modulator employing a carrier control frequency in the form of sharply squared carrier waves in the nature of an electronic switch control.

Other features and advantages not specifically enumerated will be apparent after a consideration of the following detailed descriptions and the appended claims.

In the drawing which represents one preferred embodiment of the invention, the numeral 1 represents any well-known source of intelligence signals of varying frequency which, for example, are to be converted into a higher frequency. The numeral 2 represents any well-known source of constant frequency square waves which are balanced with respect to ground. The waves from source 2 will, for convenience, be referred to as carrier waves. Preferably the amplitude of the signals from source 1 is very much smaller than the amplitude of the signals from source 2. The sources 1 and 2, instead of being of the form shown, may consist of any well-known push-pull balanced source of signals.

Associated with source 1 is a pair of grid-controlled tubes 3, 4, whose control grids 5, 6, are connected respectively across the input transformer 1 provided with a grounded midpoint secondary as is well-known in push-pull systems. The plates or anodes 8, 9, are connected in like

phase through an output load resistor 10 to the positive terminal of the D. C. plate supply source 11. The signals to be utilized are tapped off at the terminals 28, 29, across resistor 10. The cathodes 12 and 13 of tubes 3 and 4 connected in parallel through respective bias resistors 14, 15, which in turn are connected to a common resistor 16, which is returned to ground through adjustable contact 17.

The source 2 is likewise connected in balanced push-pull relation across the control grids 18, 19, of a pair of grid-controlled tubes 20, 21. The plates or anodes 22, 23 of these tubes, are connected in like phase with the positive terminal of source 11. The cathodes 24, 25, are connected by conductors 26, 27, directly to the corresponding cathodes 12, 13.

The system can be balanced by an adjustment of the contact 17, and by the suitable balanced 20 adjustment of the input circuits to grids 5 and 6, and to grids 18 and 19. For this latter purpose, a grounded midpoint transformer may be employed, or if desired a potentiometer resistance may be connected across each pair of grids and 25 with its sliding contact connected to ground. Other well-known methods of balancing the input circuits from the sources 1 and 2 may be utilized.

I have found that by using a source 2 of carrier waves of sharply squared wave shape, the phase 30 of the intelligence signals from source 1 can be reversed at the carrier frequency with a minimum production of harmonics of the intelligence frequency. This is so because the system provides a linear transfer characteristic so far as intelligence signals are concerned. There is complete suppression of the frequencies from sources 1 and 2, as well as substantial suppression of the harmonics of the intelligence frequency.

The manner of operation of the system is along 40 the following lines. As the grid 18, for example, becomes instantaneously positive for the duration of each positive square wave from source 2, tube 20 becomes conductive. The plate current of tube 45 20 flows through bias resistor 14, the voltage drop of which biases grid 5 to substantial plate current cutoff. Tube 3 therefore remains substantially non-conductive during each positive one-half cycle impressed on grid 18 from source 2. However, during this half cycle, grid 19 maintains tube 21 non-conductive with the result that 50 tube 4 is conductive and remains conducting for each positive one-half cycle impressed on grid 18. Tube 4 under these conditions, acts as a linear degenerative amplifier of unity gain if $R10=R14=R15$. When the carrier cycle from

source 2 reverses and grid 18 becomes positive, tube 4 becomes non-conductive and tube 3 becomes conductive. Tube 3 then acts as a linear degenerative amplifier of unity gain, amplifying the signal in opposite phase to that amplified by tube 4. The resultant output of tubes 3 and 4 remains substantially constant, but by reason of the balanced out-of-phase inputs to tubes 3, 4 and 20, 21, and by reason of the signal in-phase output load 10, the output at terminals 28, 29, contains large sum and difference of the frequencies from sources 1 and 2. Thus, if source 1 is delivering at any given instant, a 200 C. P. S. intelligence signal, and source 2 delivers an 1800 C. P. S. square wave carrier, the output at terminals 28 and 29 will contain 2000 C. P. S. and 1600 C. P. S. If desired, the terminals 28 and 29 may be connected to a suitable high-pass filter to pass the sum frequencies only.

While one particular embodiment has been disclosed herein, various changes and modifications may be made without departing from the spirit and scope of the invention.

What I claim is:

1. In a double-balanced modulator, a first pair of grid-controlled electron tubes with their input circuits connected in balanced push-pull relation to a source of intelligence waves, a second pair of grid-controlled tubes with their input circuits connected in balanced push-pull relation to a source of square carrier waves, a separate grid bias resistor for each tube of the first pair, said grid bias resistors being connected in divided balanced relation in the plate-to-cathode circuits of the corresponding tubes of the second pair, and a balancing potentiometer connected between said bias resistors and the midpoint of the balanced system to cause the transfer characteristic of the first pair of tubes to be substantially linear so far as said intelligence waves are concerned.

2. In a double-balanced modulator, a pair of grid-controlled tubes having their input circuits connected in balanced push-pull relation to a source of signal waves, an electronic switch comprising a pair of grid-controlled electron tubes having their input electrodes connected in balanced push-pull relation to a source of carrier frequency square-topped waves, and connections between the plate circuits of the second mentioned pair of tubes and the grid bias circuits of the first mentioned pair of tubes for alternately biasing the first mentioned pair of tubes to plate current cut-off in synchronism with said square-

topped waves, the output electrodes of said first pair of tubes being connected in like phase to a load circuit whereby the signal wave frequency and the square-wave frequency are deleted in said output circuit and the said output circuit passes substantially the sum and difference frequencies between said signal frequency and said square-wave frequency.

3. In a double balanced modulator system, a first pair of grid-controlled electron tubes having their input electrodes connected in divided balanced relation to a source of waves representing intelligence to be conveyed, a second pair of grid-controlled electron tubes having their input electrodes connected in divided balanced relation to a separate source of sharply squared carrier waves of constant frequency, means for applying the plate currents of said second pair of tubes to develop corresponding voltages and for applying said voltages in divided balanced relation to the cathodes of the first pair of tubes to cause plate current cut-off bias to be applied to said first pair of tubes alternately in accordance with the reversal of phase of the carrier waves, and a common output load circuit connected in like phase to the plates of said first pair of tubes whereby the signals appearing in said output circuit consist substantially only of the sum and difference frequencies between the waves from said two sources.

4. A double balanced modulator system according to claim 3 in which the means for developing and applying said voltages includes separate cathode resistors for the first pair of tubes so that the transfer characteristic between the input and output of each of said first pair of tubes is substantially linear so far as said intelligence signals are concerned.

5. A double balanced modulator system according to claim 3 in which the means for developing and applying said voltages includes individual cathode resistors in the cathode return circuits of said first pair of tubes to cause each tube of said first pair to act as a linear degenerative amplifier.

6. A double balanced modulator system according to claim 3 in which the means for developing and applying said voltages includes individual cathode load resistors for the first pair of tubes, said cathode load resistors having substantially the same magnitude as said plate load to cause the said first pair of tubes to act alternately as linear degenerative amplifiers of unity gain.

HERSHEL TOOMIM.
